UNITED STATES PATENT OFFICE.

WILLIAM R. COOPER, OF McDONALD, PENNSYLVANIA.

WRENCH.

SPECIFICATION forming part of Letters Patent No. 782,110, dated February 7, 1905.

Application filed October 25, 1904. Serial No. 229,942.

To all whom it may concern:

Be it known that I, WILLIAM R. COOPER, a citizen of the United States, residing at McDonald, in the county of Washington, State 5 of Pennsylvania, have invented certain new and useful Improvements in Wrenches; and I do hereby declare the following to be a full, clear, and exact description of the invention, such as will enable others skilled in the art to 10 which it appertains to make and use the same.

This invention relates to wrenches, and more particularly to adjustable wrenches, and has for its object to provide a wrench so arranged that pressure against the handle thereof in 15 one direction will cause the jaws of the wrench to tightly grip any object with which they are engaged.

A further object is to provide a wrench of this kind in which the jaws will be automatically disengaged when the strain is removed 20 from the handle.

Other objects and advantages will be apparent from the following description, and it will be understood that changes in the specific 25 construction shown may be made and that any suitable materials may be used without departing from the spirit of the invention.

In the drawings forming a portion of this specification, and in which like numerals of 30 reference indicate similar parts in the several views, Figure 1 is a side elevation of the wrench. Fig. 2 is a longitudinal section. Fig. 3 is a detail perspective view of the recessed end of the handle. Fig. 4 is a section on line 35 3 3 of Fig. 1.

Referring now to the drawings, the present invention comprises a handle 5, having one of its upper corners rounded, as shown at 6, and formed in the opposite sides of the handle 40 are arc-shaped recesses 7, which open through the rounded corner of the handle. In the upper end of the handle there is formed a triangular notch 8, with which the recesses 7 communicate, and at the side of this notch, 45 away from the corner 6, there is an upwardly-extending finger 9, having its face, which lies in the direction of the corner 6, beveled, as shown at 10.

A jaw member 11 is provided and is bifurcated at its lower end, the resultant spaced

portions being rounded to conform to the arc-shaped recesses 7, one of these spaced portions being disposed in each of the recesses, and passed centrally through these spaced portions and through the handle there is a pivot-bolt 55 12. The jaw member 11 has a jaw 13 at its outer end, and disposed against the sides of the jaw member and secured thereto are the spaced portions of a yoke 14, the bight portion 15 of which lies below the jaw 13 and 60 spaced from the forward face of the jaw member. Slidably engaged between the bight 15 and the forward face of the jaw member is a jaw-block 16, arranged for coöperation with the jaw 15, and this jaw-block is arranged for 65 engagement of its lower end against the beveled face 10 of the finger 9 and in which position it is yieldably held by a helical spring 17. In its inner face the block 16 is provided with a groove 18, which terminates short of 70 the lower end thereof. This groove receives a lug 19, which projects from the forward face of the jaw member, and the spring 17 is disposed within the groove 18 between the end thereof and the finger 19.

As shown in Fig. 1, the jaw member lies normally at an angle to the handle, and the jaw-block 16 rests with one corner in the notch 8 and at the farthest limit of its movement away from the jaw 13. The jaw 13 may 80 now be engaged with an object, and, as will be readily understood, movement of the handle 5 in one direction will cause the jaw member to rock upon the bolt 12, and the jaw-block 16, moving over the face of the finger 9, will 85 be moved in the direction of the jaw 13 to tightly grip the object with which the latter is engaged. When the handle is moved in the opposite direction, the spring 17 will return the parts to their original positions. 90

What is claimed is—

1. A wrench comprising a handle, a member pivoted to the handle and including a jaw, a jaw-block slidably connected with the member for movement toward and away from the 95 jaw and arranged for coöperation therewith, said jaw-block having a recess therein, a lug carried by the pivoted member and extending into the recess, and a spring disposed within the recess between the bottom thereof and the 100

lug, said spring being arranged to hold the jaw-block yieldably at the limit of its movement away from the first-named jaw, said jaw-block being arranged for engagement by the handle to move it against the action of the spring when the handle is moved pivotally with respect to the member.

2. A wrench comprising a handle, a member pivoted to the handle and having a jaw, a yoke secured to the member and lying with its bight spaced therefrom, a jaw-block slidably engaged between the bight and the member and arranged for movement toward and away from the jaw and for coöperation there-

with, a spring arranged to hold the jaw-block 15 yieldably at the limit of its movement away from the jaw, and a finger carried by the handle and arranged for engagement of the jaw-block to move the latter against the action of the spring, when the member is moved in one 20 direction upon its pivot.

In testimony whereof I affix my signature in presence of two witnesses.

WILLIAM R. COOPER.
